CLAIM

The ornamental design for a portable mount for citizen band radios, substantially as shown.

DESCRIPTION

FIG. 1 is a perspective view of a portable mount for citizen band radios embodying the present design;

FIG. 2 is an elevational view thereof of the side opposite to that shown in FIG. 1;

FIG. 3 is a top plan view thereof;

FIG. 4 is a front elevational view thereof;

FIG. 5 is a rear elevational view thereof; and

FIG. 6 is a bottom view thereof.
